UNITED STATES PATENT OFFICE.

DANIEL FEATHER AND ALVA CULP, OF MARION, INDIANA.

STRINGED MUSICAL INSTRUMENT.

No. 853,686.

Specification of Letters Patent.

Patented May 14, 1907.

Application filed February 28, 1906. Serial No. 303,515.

To all whom it may concern:

Be it known that we, DANIEL FEATHER and ALVA CULP, citizens of the United States, residing at Marion, in the county of Grant 5 and State of Indiana, have invented certain new and useful Improvements in Stringed Musical Instruments, of which the following is a specification, reference being had therein to the accompanying drawing.

Our invention relates to stringed musical instruments similar to mandolins and guitars, and also to resonators or sounding devices for such instruments.

One object of the invention is to provide a 15 stringed instrument of this character which will have clearer and more pleasing tones than the ordinary mandolins, guitars, and the like, and which will be of very simple construction so that it may be manufactured at 20 less cost than such instruments.

Another object of the invention is to provide an instrument of this character which will be more convenient to hold and handle.

A still further object of the invention is to 25 provide a resonator or sounding device which may be used in connection with stringed instruments such as mandolins, guitars, banjos, violins, etc., to cause them to produce much clearer and more resonant tones, and 30 which may be either built permanent in the instrument or removably attached to it.

Other objects and advantages of our invention, as well as the structural features by 35 means of which these objects are attained, will be made clear by an examination of the specification, taken in connection with the accompanying drawings, in which the same reference numerals denote corresponding parts throughout, and in which:—

Figure 1 is a top plan view of our improved 40 stringed musical instrument; Fig. 2 is a longitudinal sectional view through the same, taken on the plane indicated by the line 2—2 in Fig. 1; and Fig. 3 is a transverse sectional 45 view taken on the plane indicated by the line 3—3 in Fig. 1.

The embodiment of our invention illustrated in the drawings is very much like the ordinary mandolin, the chief differences being 50 the shape of the body 1, the provision of a frame 2 around the neck, and the provision of the resonator or sounding device 3 which latter is here shown as built in and forming an integral part of the body, but which, if desired, may be in the form of a removable attachment for stringed instruments of any de-

scription. The body 1 is made of rectangular shape, as shown, so that it may be easily manufactured at a much smaller cost than similar instruments having curved or bowl-shaped bodies. The body 1 consists of the bottom 4, the top 5 having the usual opening 6 formed therein, the upper and lower ends 7 and 8, and the sides 9 which have their upper portions 10 extended and connected by transverse pieces 11 to the neck 12 at a point adjacent to its bridge 13. The neck 12 is similar to the neck of an ordinary mandolin and projects from the center of the upper portion of the end 7, as clearly shown in Fig. 2. Upon 70 the outer end of the neck is the usual head 14 which carries the keys, pegs or similar devices 15 by means of which the strings 16 are stretched. The latter are similar to the strings of the ordinary mandolin and are 75 stretched by the devices 15 in the usual manner between the upper bridge 13 and the lower bridge 17 which latter is located upon the top 5 adjacent to the usual tail piece 18 to which the lower ends of the strings are attached and which serves as a hand rest. The extended portions 10 of the sides 9 and the transverse or cross pieces 11 form a rectangular frame which surrounds or incloses the neck 12 and serves as a support to rest against 80 the arm of the performer when the instrument is in use, as will be readily understood. This frame also permits the instrument to be readily suspended upon a peg, hook or the like on a wall.

The resonator or sounding device 3 is in 90 the form of a box or casing disposed above the upper portion of the top 5 and it may be of any shape, size and construction. As here shown, it is of rectangular shape and formed 95 by upwardly-extending integral portions 19 of the sides 9, upper and lower ends 20 and 21, and a top 22 in which latter is formed an opening 23, which is located directly above the opening 6 in the top 5 and is of less size than the same. In the lower central portions of the end walls 20 and 21 of the resonator box are slots or openings 24 through which the strings 16 extend, as shown in Fig. 2. The provision of this box 3 above the sounding 100 board or top 5 of the body 1 causes the tones produced by picking the strings to be much clearer, and more resonant and voluminous than would be the case if it were omitted, so that stringed instruments of all kinds will be 110 greatly improved by its use.

The construction, operation, and advan-

5 tages of the invention will be readily understood from the foregoing description, taken in connection with the accompanying drawings, and a further explanation is deemed unnecessary.

10 While we have shown and described the preferred embodiment of the invention, it will be understood that we do not wish to be limited to the precise showing herein set forth, since various changes in the form, proportion, and the minor details of construction may be made without departing from the spirit or sacrificing any of the advantages of the invention, as defined by the appended claims.

15 Having thus described our said invention, what we claim as new and desire to secure by Letters Patent of the United States, is:—

20 1. A stringed musical instrument of the character described comprising a rectangular body having an apertured sounding board and sides formed with horizontally extended portions at their forward ends and vertical extensions at their upper edges, a neck projecting centrally from the forward end of said body, a transverse piece connecting said neck and the extended forward end portions of said sides, slotted ends connecting the vertically-extended portions of the sides of the 25 30 body, an apertured plate connecting said ends and the vertically-extending portions of

the upper edges of said sides, and strings extending through the slots and across the apertures in said sounding board and connected at the other end with the neck, substantially 35 as shown and described.

2. A stringed musical instrument of the character described comprising a body portion, a resonator box composed of extensions formed integral with the body portion, an 40 apertured plate connecting the tops of the extensions, slotted plates connecting the edges of said extensions, said body portion comprising an apertured sounding board beneath the resonator, a neck carried by the body portion, a 45 tail piece carried by the body portion, strings stretched across the aperture in the sounding board and through the slots, said strings being connected at one end with said tail piece and at the other with the neck, a frame comprising parallel arms formed integral with the sides of the body, and a cross-piece connecting the ends of said arms and forming a rest or support for the outer portion of the neck, substantially as shown and described. 50 55

In testimony whereof we hereunto affix our signature in presence of two witnesses.

DANIEL FEATHER.
ALVA CULP.
